(57) **CLAIM**

The ornamental design for a diagonal lid panel for an egg carton, as shown and described.

DESCRIPTION

FIG. 1 is a top right perspective view of a diagonal lid panel for an egg carton.

FIG. 2 is a top plan view of the FIG. 1 lid panel for an egg carton.

FIG. 3 is a bottom plan view of the FIG. 1 panel for an egg carton.

FIG. 4 is a front view of the FIG. 1 panel for an egg carton.

FIG. 5 is a back view of the FIG. 1 panel for an egg carton.

FIG. 6 is a right side view of the FIG. 1 panel for an egg carton; and,

FIG. 7 is a left side view of the FIG. 1 panel for an egg carton.

The characteristic features of the design resides in a diagonal lid panel spanning two opposing corners of the lid and having, at each opposing corner, a flat side panel adjacent each side of the corner.

The broken lines shown illustrate environmental structure that form no part of the claimed design.

1 Claim, 3 Drawing Sheets
